ТИЛТИНГ ТОЙ РАСЕ ТРАК ПИСИ

Pasquale Iammatteo, Staten Island, N.Y., assignor to The Lionel Corporation, New York, N.Y., a corporation of New York

Filed May 14, 1965, Ser. No. 85,281

Term of patent 14 years

(Cl. D34—15)

FIG. 1 is a perspective view of a tilting toy race track piece showing my new design; FIG. 2 is an elevation view thereof; FIG. 3 is a left elevation view thereof; FIG. 4 is a right elevation view thereof; FIG. 5 is a top plan view thereof; and FIG. 6 is a bottom plan view of the base only.

FIG. 1 is a perspective view of a tilting toy race track piece showing my new design; FIG. 2 is an elevation view thereof; FIG. 3 is a left elevation view thereof; FIG. 4 is a right elevation view thereof; FIG. 5 is a top plan view thereof; and FIG. 6 is a bottom plan view of the base only.

FIG. 1 is a perspective view of a tilting toy race track piece showing my new design; FIG. 2 is an elevation view thereof; FIG. 3 is a left elevation view thereof; FIG. 4 is a right elevation view thereof; FIG. 5 is a top plan view thereof; and FIG. 6 is a bottom plan view of the base only.

The dominant features of my design reside in the portions shown in full lines.

I claim:
The ornamental design for a tilting toy race track piece, substantially as shown and described.
